UNITED STATES PATENT OFFICE.

BARRY IVOR, OF CHICAGO, ILLINOIS.

ODORLESS OIL-BURNING HEATING STOVE.

Application filed September 21, 1922. Serial No. 539,560.

To all whom it may concern:

Be it known that I, BARRY IVOR, a citizen of the United States, and a resident of Chicago, in the county of Cook and State of Illinois, have invented certain new and useful improvements in Odorless Oil-Burning Heating Stoves, of which the following is a specification.

This invention has relation to that type of stoves used for heating purposes, in which oil, preferably kerosene, is employed as fuel, and it consists in certain peculiarities of the construction, novel arrangement and combination of the various parts thereof, as will be hereinafter more fully set forth and specifically claimed.

The invention has for its principal object, the provision of a stove of such construction and arrangement of its parts, that it can be handled as a unit, thereby rendering it portable, if desired, and so that it will furnish from the fuel oil, such as kerosene, a maximum of heat, without the usual sensible dryness or lack of moisture, incident to the heat produced by oil-stoves of the type commonly heretofore in use, and so that, it will reduce to a minimum, or practically eliminate the emanation of the usual noxious, poisonous and disagreeable odors, soot, dust and gases, or in other words, will prevent the deleterious odors or fumes from the burning oil escaping into the room and commingling with the air to be breathed.

It is a further object of the invention, to provide means in a stove of the above named general character, whereby the moisture, in the air of a room in which the stove is located, will be conserved, or moisture supplied thereto as it is heated by the stove.

Other objects and advantages of the invention will be disclosed in the following description and explanation.

The invention will be explained and more readily understood when read in conjunction with the accompanying drawings, which illustrate one embodiment of the invention, it being obvious that changes and modifications may be resorted to without departing from the spirit of the appended claims forming a part hereof.

In the accompanying drawings,—

Figure 1 is a central vertical sectional view of a stove embodying the invention.

Fig. 2 is a plan sectional view partly in elevation, taken on line 2—2 of Fig. 1 looking in the direction indicated by the arrows.

Figs. 3 to 5 inclusive are plan sectional views taken on lines 3—3, 4—4, and 5—5 of Fig. 1 as indicated by the arrows, and

Fig. 6 is a view partly in section and partly in elevation of a portion of the water tank of the stove and a waste valve therefor.

Corresponding numerals of reference refer to like parts throughout the different views of the drawings.

The reference numeral 10 designates the base of the stove, which base is by preference circular in shape and provided with depending legs 11 to support it a distance 70 from the floor. The base is also provided with a concentric opening or socket 12 for the reception of a lamp which is designated as a whole by the numeral 13 and may be of any suitable size and type but the same is 75 herein shown as being of a type which employs a circular or cylindrical wick in its burner.

Mounted on the base 10 is a segmental or substantially semi-circular upright housing 14 for the lamp, which housing also serves to support the heat radiating and products of combustion drums or conduits of the device. The housing 14 is firmly secured on the base 10 by means of upright rods or 80 screw bolts 15 which serve to secure horizontally on the top edge of the housing 14 a circular and centrally apertured supporting member 16 for the heat radiating drums 85 and conduits for the passage of the products of combustion from the lamp.

As is clearly shown in Figs. 1 and 4 of the drawings, the floor or supporting member 16 is provided on its upper surface with a pair of upwardly extended flanges 17 and 18 which are concentric with the opening 19 in the member 16, as well as concentric with the periphery of said member. Secured at its lower end to the flange 17 is a drum or cylinder 20 and secured at its lower end to 100 the flange 18 is another drum, cylinder, or conduit 21, both of which extend upwardly from the supporting member 16 a suitable distance and have their upper ends secured to depending flanges 22 and 23 respectively, 105 with which a horizontally disposed circular plate or annulus 24 is provided on its lower surface. This plate or annulus has an upwardly extended flange 25 surrounding the central opening therein and is tied to the 110 supporting member 16 on the upper end of the housing 14 by rods or screw bolts 26 as

is clearly shown in Figs. 1 and 3 of the drawings.

Surrounding the upper portion of the annular flange 25 of the annulus 24 is a centrally orificed member 27 which is horizontally disposed at a distance from and above the annulus 24 and is provided at its periphery with a downwardly and outwardly extended flange 28, which flange is secured 10 to the outwardly extended peripheral flange 29 of the annulus 24 by means of screw bolts 30 or other suitable fastening devices. The downwardly extended portion of the flange 28 is provided with a series of openings 31 which communicate with openings 32 with which the annulus 24 is provided between the flanges 22 and 23 thereon. Communication between the drums or cylinders 20 and 21 is established through openings 21^a 15 in the drum 21, which openings are provided for the passage of air from the drum 21 into the upper portion of the drum 20, from whence a small quantity of air passing through the drum 21 will be discharged, but 20 in the main body of the air in said drum will be discharged through the conduit 34, as is obvious. Air will enter the drum 20 through the openings 33 in the lower portion thereof and will enter the drum 21 25 through the burner of the lamp, as is obvious.

Mounted on the upper surface of the member 27 and surrounding at its lower end the opening in said member, is an upwardly extended flue or conduit 34 which by preference is provided at its lower end with an annular flange 35 by means of which and screws 36 it is secured to the member 27. The upper end of the flue or conduit 34 is 30 provided with a horizontally disposed spider 37, which spider has centrally and rigidly secured thereon an upright rod 38 for the purpose to be presently explained.

Mounted on the outer surface of the conduit 34 at a suitable distance above the member 27 are a number of outwardly extended arms 39 which support at a distance from and around the conduit 34 a ring-like horizontal bracket 40 which has at its periphery an upwardly extended flange 41 as is clearly shown in Figs. 1 and 2 of the drawings. Supported on the bracket 40 and secured thereon by means of screws 42 extended through suitable openings in the flange 41 of said bracket, is a water tank 43 which is in the form of an annulus and has the upper edge of its inner wall inwardly deflected as at 44 to fit snugly around and preferably against the upper portion of the conduit 34. For the purpose of preventing the water in the tank 43 from boiling or becoming too hot, a lining 45 of asbestos located around the conduit 34 between it and said tank, is sometimes employed. 50 However, it will be observed in Fig. 1 that

the central opening of the tank 43 is considerably larger than the conduit 34 and that thus an air space between the tank 43 and the conduit 34 will be provided.

Located in the tank 43 is a dome-shaped deflector 46 which has centrally mounted thereon a tube 47 for slidable co-operation with the rod 38 of the discharge flue or conduit. The deflector 46 is made of some light sheet material, such as aluminum, and has its periphery formed with an inverted trough 48 which is curved in cross-section and has secured on its lower surface a number of floats 49 of any suitable material and construction. These floats are slightly segmental in shape and spaced apart at their ends, as clearly shown in Fig. 2, for the purpose of permitting heated air passing there-between on the surface of the water in the tank 43 and below the peripheral edge of the deflector.

As a further support for the bracket 40 and the water tank 43 thereon, upright posts 50 are interposed between the member 27 and the aforesaid bracket. Slidably mounted for vertical movement in the opening 19 of the supporting member 16 on the upper end of the housing 14 is a cylinder or conduit 51 which has its upper end open and its lower end provided with a horizontally disposed and inwardly extended plate 52 for partially closing the lower end of the said cylinder. The plate 52 is provided with a central opening around which is an upwardly extended flange 53, which flange surrounds the burner of the lamp when the cylinder 51 is in its operative position as shown by continuous lines in Fig. 1 of the drawings, in which view it will be understood that the plate 52 will rest on an annular flange 54 of the lamp burner so that air may be supplied to the burner through a perforated portion 55 thereof located just below said flange. When it is desired to remove the lamp from the stove the cylinder 51 may be slid upwardly to about the position shown by dotted lines in Fig. 1, in which position it may be supported by means of a hook 56 pivoted to and depending from a lug 57 on the lower surface 105 of the top of the lamp housing.

The lower front portion of the slidable cylinder 51 may be provided with an opening 58 and a covering 59 of mica or the like therefor, secured at its edges to the cylinder 51 around its opening for the purpose of permitting the flame of the lamp burner to be seen when the cylinder is in its lowered position. The water tank 43 is provided in its bottom with an opening 60 which registers with an opening 61 of larger diameter in the bracket 40. A tube 62 having a flange 63 to rest on the upper surface of the floor of the tank 43 and provided with an opening 64 just above said flange, has its 110 115 120 125 130

lower end located in the openings 60 and 61 and is held in position by means of a lock nut 65 screwed onto the tube 62 and against the bracket 40. Communicating with and secured to the lower end of the tube 62 is a drain pipe 66 through which water from the tank may be discharged when desired. Screwed into the upper end of the tube 62 is a hollow tube 67 which has on its lower 10 end a valve to close the opening 64 of the tube 62 so as to prevent discharge of water from the tank until desired. When screwed down so that the lower portion or valve of the tube 67 will close the opening 64, it is 15 manifest that the tank 43 may be supplied with water until it overflows the upper end of the tube 67 when the excess water will be discharged through said tube and the drain pipe 66, thus preventing overflow of 20 the tank.

Detachably mounted on the upper end of the tank 43 is a dome-shaped cover 68 which may be provided with a knob or handle 69 for the removal of said cover. This cover is perforated as shown in Fig. 1 to permit of the free passage of the heated air from the water chamber. From the foregoing and by reference to the drawings, it will be readily understood and clearly seen that 30 by placing a lamp in the socket of the base 10 therefor, and lighting the wick of the lamp, the cylinder 51 can be lowered from the dotted line position shown in Fig. 1, to the position shown by continuous lines 35 in said figure, when a draft will be created through the perforated portion 55 of the lamp, thus causing the products of combustion and heated air to ascend through the upright casing provided by the cylinder 51, the drum 21, and the conduit 34, and from thence into the cavity of the deflector 46, the floats of which are supported by the water in the tank which surrounds said conduit.

45 Vertical movement of the deflector owing to the evaporation of the water in the tank will be permitted by reason of the slidable tube 47, through which the rod 38 on the upper end of the conduit is extended. The heated air, as it passes from the upper end of the conduit 34, as well as the products of combustion, will be deflected by the deflector 46 and caused to come in contact with the surface of the water in the water tank. As 50 the floats 49 which support the deflector are spaced apart at their ends, and as the perimeter of the deflector 46 is maintained a slight distance above the surface of the water, it is manifest that the heated air, 55 after being subjected to contact with the water, will pass out through the spaces between the floats and from thence upwardly in the tank and out through the perforations of the cover 68 as is indicated by the arrows 60 in Fig. 1 of the drawings.

In the operation of the stove the water in the tank will be heated to a considerable degree but not to the boiling point, which would create too rapid evaporation of the water. As the heated air and products of 70 combustion are forced downwardly by the deflector 46, and into contact with the water, it is manifest that the air will pass between the ends of the floats in practically a pure condition and without deleterious odors, yet 75 carrying humidity about equal to that of the atmosphere.

Having thus fully described my invention, what I claim as new and desire to secure by Letters Patent is—

1. In a stove of the class described, the combination with an upright casing, of a fuel burner located in the lower portion of said casing, a water container horizontally supported around the upper portion of the 85 casing, and means above the upper end of the casing and supported by the water in said container for deflecting heated air and the products of combustion from said fuel burner against the water in said container. 90

2. In a stove of the class described, the combination with an upright casing, of a fuel burner located in the lower portion of said casing, a water container horizontally supported around the upper portion of the 95 casing, and means above the upper end of the casing and supported by the water in said container for deflecting heated air and the products of combustion from said fuel burner against the water in said container, 100 said deflecting means having passages for the outlet of the heated air.

3. In a stove of the class described, the combination with an upright casing, of a fuel burner located in the lower portion of 105 said casing, a water container horizontally supported around the upper portion of the casing, and vertically movable means above the upper end of the casing for deflecting heated air and the products of combustion 110 from said fuel burner against the water in said container.

4. In a stove of the class described, the combination with an upright casing, of a fuel burner located in the lower portion of 115 said casing, a water container horizontally supported around the upper portion of the casing, and vertically movable means above the upper end of the casing supported by the water in said container for deflecting heated air and the products of combustion from 120 said fuel burner against the water in said container.

5. In a stove of the class described, the combination with an upright casing having 125 a vertically slidable lower section, of a fuel burner located in the lower portion of said casing, a water container horizontally supported around the upper portion of the casing and having its upper end open, a dome- 130

shaped deflector located above the upper end of the casing and having its periphery extended into said container, and means on the deflector for causing the same to float in said container.

6. In a stove of the class described, the combination with an upright casing, of a fuel burner located in the lower portion of said casing, a water container horizontally

supported around the upper portion of the 10 casing and having its upper end open, a dome-shaped deflector located above the upper end of the casing and having its periphery extended into said container, and spaced floats on the periphery of the deflector to cause the same to float in said container. 15

BARRY IVOR.
